UNITED STATES PATENT OFFICE.

LEE C. EAST, OF OMAHA, NEBRASKA.

SHOE-HEEL ATTACHMENT.

1,071,147.

Specification of Letters Patent. Patented Aug. 26, 1913.

Application filed January 18, 1913. Serial No. 742,821.

To all whom it may concern:

Be it known that I, LEE C. EAST, a citizen of the United States, residing at Omaha, in the county of Douglas and State 5 of Nebraska, have invented certain new and useful Improvements in Shoe-Heel Attachments, of which the following is a specification.

This invention relates to a shoe heel attachment of the class adapted to prevent slipping on ice or like surfaces, and has for its object to provide an article for this purpose which will be durable in wear, effective for the purposes described, and which 15 may be economically manufactured.

The invention consists of the novel construction, combination and arrangement of parts as described herein and claimed, and as illustrated in the drawing, wherein,—

20 Figures 1 and 2 are plan views of the device, applied to the bottom of a shoe heel, Fig. 2 showing the prongs when thrown outwardly of the bearing-plate, Fig. 1 showing the prongs when withdrawn from their outward position. The remaining figures, with the exception of Fig. 16, are on an enlarged scale. Figs. 3 and 4, respectively, are plan and front views of the housing plate. Fig. 5 25 is a plan view of the operating-plate. Fig. 6 is a view of the operating-plate, being a section on line 6 6 of Fig. 5. Fig. 7 is a plan view of the inner side of the bearing-plate. Fig. 8 is a sectional view of the 30 bearing-plate, on line 8 8 of Fig. 7. Fig. 9 is an end view of the housing-plate. Fig. 10 is an end view of the operating-plate. Fig. 11 is an end view of a two-pronged tooth member. Figs. 12 and 13 are plan 35 views of the same. Fig. 14 is a transverse section through the shoe heel, the view being enlarged and on line 14 14 of Fig. 2. Fig. 40 15 is a sectional view, enlarged, on line 15 15 of Fig. 1. Fig. 16 is a transverse section on line 16 16 of Fig. 2, the parts 45 being shown as reversed or inverted.

Referring now to the drawing for a more particular description, numeral 1 indicates the heel of a shoe having a suitable recess 50 2 formed to open upon its bottom, within which the device may be seated and secured to the heel by keepers or screws 3.

At 4 is indicated a bearing-plate formed with apertures 5, and suitably journaled in 55 the plate and adapted to be normally disposed in apertures 5 are tooth-members 6.

While I have shown three of said apertures and three teeth, any lesser or greater number may be employed, if desired. Each tooth-member is preferably of V-shape to 60 provide prongs *a* and *b* and, preferably, these prongs are formed tapered outwardly from the base *c*; and the base may be provided at its ends with pivots or trunnions *d* for mountings in suitable grooves *e* 65 formed in the bearing-plate, said grooves opening upon the inner face of said plate and upon apertures 5. Means are provided for causing coincident, swinging movements of the tooth-members in an arc of substantially 70 90 degrees, and for maintaining them after they have been swung, so that prong *a* of each tooth-member will be disposed outwardly of and at substantially right angles to plate 4, prongs *b* being then disposed in apertures 5. 75

At 7 is indicated an operating-plate adapted to be reciprocated longitudinally by manually moving its handle 8. It is provided at longitudinal intervals with 80 apertures 9, the transverse walls of said apertures being of wedge-shape or inclined, as indicated at *f*. Prong *b* of each tooth-member 6 is preferably formed with an outwardly extending point or projection *g*. 85 Since the prongs *a* and *b* of each tooth-member are of the same thickness, substantially, as plate 4, projections *g* may be disposed within apertures 9 of the operating-plate, outwardly of the plane of said plate 4, and 90 by referring to Fig. 14 of the drawing it will be seen that when the operating-plate is moved in one direction, the inclined walls *f* of plate 7 will engage projections *g* and thereby will cause prongs *b* to be elevated. 95 prongs *a* thereupon being swung toward apertures 5.

At 10 is indicated a housing-plate provided with apertures 11. It has a width somewhat less than plate 4, and preferably 100 it is bent angularly near its side edges to provide supports or spacing-members *h*, and when the parts are assembled, members *h* are adapted to bear upon the inner side of plate 4. Screws or keepers 3 are 105 adapted to traverse plates 4 and 10 when the device is secured in recess 2, and by reason of the construction, the operating-plate 7 is slidably mounted between said plates 4 and 10. 110

In practice, the operator may cause longitudinal reciprocation of plate 7 by manual

use of its handle 8, wall *h* having a recess *i* formed therein (Fig. 3) and traversed by a part of said handle; and recess *i* has a suitable length so that the handle may move a sufficient distance to cause a swinging movement of each tooth-member 6 in an arc of substantially 90 degrees.

At *h* is indicated a ledge, elongated lug or projection formed on the edge of plate 10 adjacent to recess *i*, and in operation it is an obstruction to the free movement of handle 8. The adjustment is such, however, that this handle, since it is elastic, may be forcibly moved to occupy a position at either 15 end of ledge *h*, said handle frictionally engaging said ledge during its movements, and in operation, the elongated lug or ledge *h* tends to prevent any longitudinal movement of plate 7, after said handle is disposed 20 at one of the ends of said ledge.

It will be understood that the provision of the operating-plate with its handle, during one of its movements, is to cause prongs *a* to move from their normal position in apertures 5 to be disposed outwardly of and substantially at right angles to plate 4, so that these prongs may prevent slipping of the shoe on ice or similar surfaces, also to cause prongs *b* at this time to be disposed 25 in apertures 5 to prevent foreign substances 30 from entering therein.

By referring to Fig. 14 of the drawing it will be seen that when prongs *a* are projecting outwardly of apertures 5, plate 7 will 35 bear upon the prong *b* of each tooth-member and will prevent any lateral movement of prongs *a*, this obviously being a desired feature, so that said prongs *a* may adequately bear all stresses to be sustained by 40 them. It will be noted that, at this time, no stresses are sustained by the pivots *d*, the pressure being communicated from prongs *a* to plates 7 and 10, and therefore the parts 45 are considered to be durable. The opposite movement of the operating-plate and its handle will cause upward swinging movements of prongs *b* from apertures 5, and when the shoe is in use, the stresses will be sustained by plates 4, 7 and 10, prongs *a* 50 being then disposed in the plane of the bearing-plate, within apertures 5.

Among some of the advantages to be derived by use of the herein described shoe heel attachment, it may be stated that the 55 parts are few and simple and may be conveniently manufactured. The teeth may be swung coincidently and conveniently for the purposes described, and the arrangement for sustaining stresses is such that the liability 60 is quite remote for a breakage or injury of any of the parts. While I have illustrated and explained these parts in detail to describe one embodiment of the invention, I do not wish to be understood as limiting myself to exactness of construction, the scope 65

of the invention being determined by the claims.

What I claim and desire to secure by Letters Patent is,—

1. An attachment for the purpose described, comprising a bearing-plate provided with a triangular aperture; a pivotally mounted substantially V-shaped tooth-member providing tapered prongs and adapted to have swinging movements to dispose said 75 prongs, in alternation, in said aperture.

2. An attachment for the purpose described, comprising a bearing-plate provided with an aperture; a pivotally mounted tooth-member provided with prongs substantially conforming in shape to said aperture and arranged to have swinging movements to dispose said prongs, in alternation, within said aperture. 80

3. A shoe heel attachment comprising a bearing-plate provided with a plurality of triangular apertures, pivotally mounted V-shaped tooth-members forming prongs conforming substantially to the shape of said apertures; means to rotate said tooth-members coincidently in an arc substantially of 90 degrees the prongs of each tooth-member being disposed in alternation, within said apertures. 90

4. A shoe heel attachment comprising a bearing-plate provided with a plurality of apertures; a plurality of tooth-members each consisting of a pair of connected prongs substantially conforming in shape to the form of the apertures of said bearing-plate; means to cause swinging movements of said tooth-members, the prongs of each member being disposed, in alternation, within said apertures, and so arranged that one of said prongs of each tooth-member will be disposed outwardly of and substantially at right angles to said plate at the time the other prong thereof is disposed in one of said apertures. 100

5. An attachment of the class described, comprising an apertured bearing-plate; tooth-members, each consisting of a pair of connected prongs substantially conforming in shape to the form of said apertures; an operating-plate bearing upon the bearing-plate; means to cause longitudinal reciprocation of the operating-plate to dispose the prongs of each tooth-member in alternation in the apertures of the bearing-plate, one of the prongs of each tooth-member being disposed outwardly of said plate at the time the other prong thereof is disposed in one of said apertures; and means tending to prevent a longitudinal movement of the operating-plate. 110

6. In a shoe heel attachment, the combination of an outer, apertured bearing-plate, an inner housing-plate in engagement therewith; a plurality of tooth-members provided with prongs and carried by the bear- 120 130

ing-plate; and an operating-plate movable intermediate the housing-plate and bearing-plate for causing the prongs of each tooth-member to be disposed, in alternation, with-
5 in an aperture of the bearing-plate.

7. In a shoe heel attachment, the combination of an outer, apertured bearing-plate, an inner housing-plate contact therewith; a plurality of tooth-members provided with
10 prongs and carried by the bearing-plate; an operating-plate movable intermediate the housing-plate and bearing-plate for causing the prongs of each tooth-member to be disposed, in alternation, within the apertures
15 of the bearing-plate; and means tending to prevent a movement of the operating-plate after a prong of a tooth-member is disposed in an aperture of said bearing-plate.

8. In a shoe heel attachment, the combination of an outer, apertured bearing-plate, 20 an inner housing-plate in engagement therewith; an operating-plate provided with a lever and disposed between the housing-plate and bearing-plate; a plurality of pivotally mounted tooth-members; said 25 lever being movable to cause sliding movements of the operating-plate, the prongs of each tooth-member engaging, in alternation, within the apertures of the bearing plate.

In testimony whereof I have affixed my 30 signature in presence of two witnesses.

LEE C. EAST.
